UNITED STATES PATENT OFFICE.

RICHARD EASTWOOD, OF COLNE, ENGLAND.

KEY ACTION OF UPRIGHT PIANOFORTES.

Application filed November 15, 1920, Serial No. 424,262, and in Great Britain November 19, 1919.

This invention relates to the key actions of pianofortes, and has for its main object to provide an improved arrangement of such actions which will facilitate the rapid repetition of a note. Other objects and advantages of the invention will appear from the following description.

According to the invention, a pianoforte key action comprises means adapted to rigidly hold the hammer a short distance from the string after the key has been pressed down and the blow from the hammer imparted to the string, such means being also adapted upon a slight release of the key to release the hammer and allow the jack, hopper or striker (hereinafter referred to as the jack), to again engage therewith to enable a further blow to be immediately struck to repeat the note. A further feature of the invention comprises a braking means for the return or backward movement of the hammer on the release of the key.

In the accompanying drawing, Fig. 1 is a more or less diagrammatic view of one embodiment of the invention showing the parts of the key action in the normal position, Fig. 2 is a like view showing the parts in the positions they occupy when the key is depressed to sound a note and held down, Fig. 3 is a like view showing the re-engagement of the jack with the hammer but after a very slight release movement of the key, and Fig. 4 is a detached perspective view of a detail of the action hereinafter more specifically referred to. Figs. 5, 6, 7 and 8 are corresponding views to Figs. 1, 2, 3 and 4, respectively, of another embodiment of the invention.

In the drawings and the following description, similar characters of reference indicate similar parts.

Referring first to Figs. 1 to 4, 1 is the key of the action, 2 the balance rail whereon the key rocks, 3 the prolong with which the rear end of the key co-acts and which is pivoted at its lower end to one end of a link 5, the other end of which is pivoted to a flange on the rail 6, and pivoted at its upper end to the lower lever or wippen 7 which is pivoted at 8 to a flange on the hammer rail 9. 10 is the jack pivoted at 11 on the lever 7 and provided with the usual flange or set-off 10^a between which and the lever 7 the usual spring 12 is arranged. 13 is the hammer comprising the butt 13^a which is pivoted at 4 to a flange on the rail 9 and provided

with the usual shoulder or notch 13^b for the engagement of the upper end of the jack 10, the stem 13^c, and the head 13^d. 14 is a shank carried by the hammer butt 13^a and 60 which may conveniently be the usual check button shank, and 15 is a button carried by the free end of the shank 14 and which may conveniently be the usual check button. 16 is the customary tape connecting the button 15 65 to the tie 17 on the lever or wippen 7.

The usual check is dispensed with and in its place there is mounted on the jack 10 a two-limbed member 18, the limbs 18^a, 18^b of which are of unequal length and co-operate with the shank 14 and the button 15 respectively. Conveniently and as shown in Fig. 4, the member 18 is constituted by a piece of stout wire bent to form a looped portion 18^c for adjustable attachment to the jack by a screw 19, and the limbs 18^a, 18^b, the ends 18^a, 18^b of which are bent at right angles. The end 18^a of the short limb 18^a lies below and is adapted to engage with, the underside of the shank 14 while the long 70 limb 18^b extends clear of the shank 14 and its end 18^b is adapted to engage with the button 15.

Normally, the parts of the action are in the position shown in Fig. 1, and on depression of the key 1 the jack 10 actuates the hammer 13 to strike the string 21 and then disengages the shoulder or notch 13^b of the hammer butt 13^a by reason of the engagement of its set-off 10^a with the set-off button 20 all in the usual way. After the hammer strikes the string, and while the key is held down, there is the customary slight rearward movement of the hammer. On this rearward movement of the hammer 95 taking place the shank 14 and button 15 are engaged by the limbs 18^a, 18^b of the member 18 on the jack 10. The end 18^a of the short limb 18^a engaging below the shank 14 supports same and presses the hammer forward 100 and the button 15 against the end 18^b of the long limb 18^b, which latter presses the hammer rearward and the shank 14 against the short limb 18^a, the hammer being thus held at a short distance from the string 21 against movement in either direction, as shown in Fig. 2. A slight release movement of the key 1 serves to release the hammer and to allow the jack 10 to again engage the shoulder or notch 13^b of the butt thereof to repeat the note with little or no further rearward movement of the hammer, which dur- 105 110

ing the re-engaging movement of the jack is supported by the end 18^a of the short limb 18^a riding over the surface 29.

In the embodiment illustrated in Figs. 5 to 8, the customary check 22 is retained and the short limb 18^a aforesaid of the member 18 is dispensed with. In place of the said short limb 18^a, the check button 15 is provided with means whereby after the key has been depressed to cause the hammer to strike the string 21 and the key is held down, the check button 15 and hammer 13 are supported by the check 22 during a subsequent slight release movement of the key to enable the jack 10 to again engage with the shoulder or notch 13^b of the hammer butt 13^a with a very small rearward movement of the hammer. Conveniently, the check button 15 is provided with a lip 23 which when the key 1 has been actuated to cause the hammer 13 to strike the string 21 and is held down, engages with the upper edge of the check 22. The check button 15 itself also engages the check 22 and the limb 18^b of the member 18, as before, engages the check button, by which means the latter is held between the check 22 and the limb 18^b and the hammer held a short distance from the string 21, against movement in either direction. On a subsequent slight release movement of the key 1, the check button 15 and hammer 13 are supported by the engagement of the lip 23 with, and the riding thereof over, the upper edge of the check 22 while the jack again engages with the hammer butt, very little rearward movement of the hammer taking place during the engagement of the jack with the hammer butt.

As in the key actions described above, the hammer is held against movement in either direction when the key is depressed and held down, all possibility of the hammer rebounding is obviated, and the hammer may, therefore, be held nearer the string than in other actions, thereby reducing the backward movement of the hammer when the key is slightly released to re-engage the jack therewith for repetition of the note.

In order to further prevent or control backward movement of the hammer during the release of the depressed key to reengage the jack with the hammer butt for the repetition of the note, (in passing from the position of Fig. 2 to that of Fig. 3) there may be provided in conjunction with the hammer a braking means which may conveniently comprise a block or shoe 24 pivotally connected by an arm 25 to the hammer butt 13^a and a rail 26 over which the block or shoe is adapted to ride. The block or shoe and the rail may be covered or provided with felt, leather or other equivalent friction or roughened surfaces 27. The operative surface of the block or shoe may be beveled as

at 28 and the rail 26 may be mounted on end pivots 30 on or about which it can be adjusted to regulate as desired the resistance offered to the movement of the block or shoe thereover when the hammer moves rearward. 70

What I claim as my invention and desire to secure by Letters Patent is:—

1. A key action for pianofortes, comprising means adapted after the key has been depressed and the hammer blow imparted to 75 the string, to positively hold the hammer a short distance from the string against movement in both directions, and also adapted on a subsequent slight release movement of the key to free the hammer and allow the jack to 80 re-engage same for the repetition of the note and brake means retarding the fall of the key upon said subsequent release.

2. A pianoforte key action according to claim 1 in which the means comprises, a 85 member mounted on the jack and comprising two limbs, one of which presses the hammer forward and the other of which presses same rearward after the key is depressed and the blow of the hammer imparted to the string, 90 and thereby positively holds the hammer a short distance from the string.

3. A key action for pianofortes having an operating key and hammer, said action comprising means including a jack for operating 95 the hammer to strike a blow, said hammer having a shank extending therefrom and carrying an abutment, a member on said jack and having two arms, one of which arms engages and moves along the under side of 100 the shank and presses the hammer forwardly, and the other arm of which engages with said abutment to press the hammer rearwardly, means for causing a movement of the jack at the end of the key stroke for 105 stopping further driving action of the jack upon the hammer and for moving said member to press the abutment and hammer rearwardly a short distance, the two arms then holding the hammer in that position against 110 movement in both directions until the key is released, the engagement of an arm of the member with the abutment being above the shank, and brake means retarding the fall of the key upon its release. 115

4. In a pianoforte key action, a braking device operating independently of the wippen adapted to retard the rearward movement of the hammer on the release of the key after same has been depressed and the 120 hammer blow imparted to the string.

5. A pianoforte key action according to claim 4, in which the brake device comprises a block or shoe pivotally connected to the hammer and a rail, the block being mounted 125 to ride over a rail in frictional engagement therewith.

6. In a pianoforte key action, a braking device operating independently of the wippen adapted to retard the rearward move- 130

ment of the hammer on the release of the key after same has been depressed and the hammer blow imparted to the string, said braking device comprising a shoe pivotally connected to the hammer and a rail, said shoe being mounted to ride over the rail in frictional engagement therewith, said rail being angularly adjustable for the purpose of varying the resistance offered thereby to the movement of the shoe thereover.

7. In a key action for pianofortes, a jack, a hammer upon which the jack operates and having an extension, with an arcuate under surface which has a center of curvature substantially coincident with the pivot of the jack when the key is depressed and the hammer has rebounded, a member carried by the jack and having a portion extending beneath the arcuate surface of the extension to limit the return movement of the hammer when the jack becomes disengaged from the hammer, the hammer being held in substantially the same position during the early part of the release of the key while the member

rides along the arcuate surface as the jack moves into driving reengagement with the hammer.

8. In a key action for pianofortes, a jack, a hammer upon which the jack operates and having an extension, a member carried by the jack and having two limbs, both adapted to engage the extension, one of the limbs limiting the rearward movement of the hammer and the other pressing the hammer away from the string.

9. In a key action for pianofortes, a jack, a hammer operated by the jack, means carried by the jack and operative when the jack is disengaged from the hammer for resiliently pressing the hammer away from the string, and means operable concomitantly with said jack for limiting rearward movement of the hammer while the key is depressed and the jack is disengaged from the hammer.

In witness whereof I have hereunto set my hand.

RICHARD EASTWOOD.
